UNITED STATES PATENT OFFICE.

FRED E. PLANETT, OF OAKLAND, CALIFORNIA, ASSIGNOR TO PLANETT MANUFACTURING COMPANY, OF OAKLAND, CALIFORNIA, A CORPORATION OF CALIFORNIA.

CORNER BEAD.

Application filed April 22, 1924. Serial No. 708,214.

To all whom it may concern:

Be it known that I, FRED E. PLANETT, a citizen of the United States, residing at Oakland, in the county of Alameda and State of California, have invented certain new and useful Improvements in Corner Beads; of which the following is a specification.

My invention relates to metallic angle or corner beads, and in particular to the type employed at the angles in plastering and cement work, both indoors and out.

Present corner beads of metal that I am familiar with, consist of a unit strip of sheet-metal formed angularly with two flanges and with a small round ridge at the meeting angle. Each flange of the bead is perforated with holes, the plaster oozing through the holes as the same is being spread on the furred walls. The ridge acts as a thickness gage for the plaster and the holes serve as a key for holding the plaster at the angles.

For indoor work this type of bead, when the plaster is not too hard, serves fairly well, but when applied to the angles of exterior work it is not efficient, because cement-coated walls employ a harder and stiffer plaster and are reinforced with wire lathing. The latter should extend around the corners and angles, but owing to the difficulties encountered in trying to position the present corner bead over the irregularly bent and more or less unyielding wire mesh lathing, it is easier to affix the corner bead direct to the wood or sheathing support, then cut and fit the wire lathing to the bead flange. This is invariably carelessly done, resulting in due time in a cracked wall near the corner. Also the spread plaster does not thoroughly get through the holes and behind the flanges to fill up the angle space therebetween. For durable construction the plaster at the corners and angles should be well worked in thereat.

The major object of my invention is to overcome the above difficulties and inefficiencies by the provision of an all-wire corner bead of simple construction, easily applicable to angles and adapted to permit the plaster or other coating to thoroughly and easily mesh around and between the wire.

Another important object is the provision of a corner bead that can be just as easily applied to a corner having wire mesh lathing extending around the same as in ideal

outdoor corner-construction work, as a corner not requiring such reinforcement as in indoor work.

A further object is to provide the bead with rigid abutting or bearing surfaces, for definite and accurate outstanding spacing means for the longitudinal rod of the bead.

I attain the above objects by the novel construction of my corner beads, and other objects and advantages of the invention will appear in the subjoined description of the accompanying sheet of drawings, in which:

Figure 1 is a horizontal section of a corner of outdoor construction work, such as the corner of a cement-coated bungalow, and has my invention applied thereto.

Fig. 2 is a side elevation of Fig. 1 showing my invention in full and but part of the corner construction, the plaster having been omitted in order to show how easily my corner bead can embrace the wire mesh lathing and the staple end enter any mesh opening.

Fig. 3 is a top view of a modification of the invention and Fig. 4 an elevation of it.

Adverting to the drawings: the numeral 5 represents an outside corner of a building, such as a bungalow, and to the surface of which has been applied in any of the usual ways the building-paper 6, and the wire mesh lathing 7 for plaster reinforcement. The lathing has been turned or extended around the corner as shown clearly in Fig. 1, and outstands a fixed distance from the wall surface by common furring devices (not shown). My invention consists of a stout and stiff wire rod 8 having lateral branches in the form of shouldered staples 9, 10 being the shoulders and bearing surface to outstand the rod 8 a definite predetermined distance from the corner. These staples are also of wire and of lighter gage than the rod, and are rigidly secured to the rod preferably by spot-welding as I have found this manner of securement very practical. The welded parts result in an integral and homogeneous efficient union as shown in section at 11, Fig. 1.

The staples are spaced at intervals along the rod 8, Figs. 2 and 4, and secured thereto at right angles and in alignment. In Figs. 1 and 2, I have shown the staple substantially in the shape of the letter U, with the extremities turned to form the eyelet 12 for the reception of securing means such as

flat-headed nails 13. The bearing faces of the eyelet ends are normally positioned at right angles to each other.

In Figs. 3 and 4, the staple shown is of simpler and cheaper construction, but not as efficient as the other and preferred form.

In the application of the corner bead of Figs. 1 and 2, the eyelet ends are simply inserted through the wire mesh openings

10 14, and the bearing faces and shoulders will immediately seat the bead, and the nails 13 may then be driven in any or all eyelet holes. In the application of the modified bead, the staple is also inserted similarly 15 through the mesh openings, and the staple leg 15 driven in to the shoulder 10. One may position and drive the latter bead in by sight, or mark or scribe a gage line parallel with the corner edge, or use a gage 20 board.

In Fig. 1, 16 represents the first coat of plaster which is spread flush with the furring surface and the furred outstanding depth of my staple legs, and 17 represents 25 the finishing coat of plaster spread flush with the outer surface of the rod 8. The dot-and-dash line 18 of Fig. 3 represents the finished surface when the modified bead is employed.

30 It is evident that when my corner bead is

used, the plaster or cement, whether soft or hard and stiff, will easily mesh around the rod and wire staple and leave no voids or unfilled spaces subject to corrosion and weakness of the corner structure.

Having thus illustrated and described my invention, what I claim as new and desire to secure by Letters Patent of the United States, is the following:

1. A unitary corner bead construction of the character described, comprising a stiff longitudinal rod having staples integrally and rigidly connected thereto at spaced intervals, said staples provided with shoulders to abut the wall and outstand the rod from the wall a predetermined distance. 40

2. In combination with the corner portion of a wall provided with an outstanding reinforcing wire mesh lathing thereat, of a corner bead adapted to embrace the lathing comprising a longitudinal rod having staples rigidly connected thereto adapted to outstand the rod from the corner a fixed distance, and the termination of the staples adapted to be inserted through the mesh openings of the lathing thereby preventing interference between the lathing and the bead at the said corner. 50

In testimony whereof I affix my signature.

FRED E. PLANETT. 55
